UNITED STATES PATENT OFFICE.

WILLIAM A. TURNER, OF WORCESTER, MASSACHUSETTS, ASSIGNOR TO
EDMUND CONVERSE, OF SAME PLACE.

DIE-PRESS.

SPECIFICATION forming part of Letters Patent No. 512,415, dated January 9, 1894.

Application filed July 7, 1891. Serial No. 398,665. (No model.)

To all whom it may concern:

Be it known that I, WILLIAM A. TURNER, a citizen of the United States, residing at Worcester, in the county of Worcester and State of Massachusetts, have invented a new and useful Improvement in Die-Presses, of which the following is a specification, reference being had to the accompanying drawings, forming a part of the same, and in

which—

Figure 1, represents such portions of a die press as are necessary to fully illustrate the nature of my present invention, the figure showing the die boxes and dies and also the reciprocating punch, or sleeve, by which the blank is cut from the metal sheet in central sectional view, the several operating parts being shown in their normal position. Fig. 2, represents the same, showing the position of the operating parts as the blank is about to be brought between the reciprocating punch and the lower die. Fig. 3, represents the same, with the several parts in the position assumed at the completion of the operation of compressing the blank between the reciprocating punch and the lower die and cutting a circular disk from its center. Fig. 4, represents the same, showing the position of the several parts after the reciprocating dies have been partially reversed and the completed blank lifted from the lower die, and Fig. 5, represents a bottom view of the latching mechanism; and Fig. 6, is a view of the sliding rods F, F', with the sleeves F², shown in sectional view.

Similar letters refer to similar parts in the different figures.

My present invention relates to certain improvements in die presses employed in cutting and stamping sheet metal in which two dies having coincident axes are employed and it consists in providing means, whereby the blank is held against the end of the reciprocating punch in its passage from one to the other of the dies.

The general construction and operation of a die press for cutting and stamping sheet metal are so well known that in the accompanying drawings I have shown only such portions as are necessary to illustrate the nature of my invention.

Referring to the drawings the line A, A, denotes the upper face of a bed or table upon which the die boxes B, C, are supported one placed above the other leaving an open space D, between them. The upper die box B, contains a die B', the diameter of its upper portion at B², being equal to the diameter of the reciprocating cutting sleeve E, and the lower portion of the die B', having its diameter reduced forming a shoulder B³. Within the sleeve E, is a reciprocating punch E', the sleeve E, and punch E', having a reciprocating motion by means of suitable actuating cams in the ordinary and well known method employed in die presses of this class. In the die box C, I place the die C', with its axis coincident with the axis of the die B', provided with a plain upper surface and having a concentric opening C². Extending below the lower die box C, is a tube C³, having annular flanges C⁴, and C⁵. The flanges C⁴, and C⁵, are provided with coincident holes forming ways for the sliding rods F, F', which pass through coincident holes in the die box C, and lower die C'. The lower portions of the rods F, F', are screw-threaded as shown in Fig. 6, to receive the screw-threaded sleeves F², and nuts F³. Between the ends of the sleeves F², and nuts F³, is securely clamped a yoke F⁴, by which the two rods F, and F', are connected. The upper ends of the sleeves F², are provided with flanges F⁵, carrying upon their upper surfaces rubber washers F⁶, and between the flanges F⁵, of the sleeves F², and the annular flange C⁵, I place the spiral springs F⁷, by which the rods F, F', are forced upward in the position shown in Fig. 1, with their upper ends flush with the upper surfaces of the die B', the screw-threaded sleeves F², and nuts F³, allowing the rods F, F', to be vertically adjusted to bring their upper ends in the desired position with upper dies B', of varying thicknesses. The rod F, is provided with an annular groove G, to receive the end of a latch G', which is pivoted at G², upon the under side of the flange C⁴, and is pressed against the rod F, by means of a spring G³, acting against a lug G⁴, upon the flange C⁴, the tension of the spring G³, being adjusted by the screw G⁵, held in the lug G⁴. The latch G', is provided with a notch G⁶, to re-

ceive a cam plate G^7 , having an inclined surface G^8 , and attached to a sliding rod G^9 , sliding in ways in the lower die box C , and the annular flange C^5 . The rod G^9 , has a fixed 5 collar G^{10} , between which and the flange C^5 , is a spring G^{11} , by which the rod G^9 , is forced upward bringing its upper end flush with the upper surface of the upper die B' , its upward movement being limited by means of a nut 10 G^{12} , which strikes the flange C^5 , and is adjustable upon the screw-threaded section G^{13} , of the rod G^9 . The rod G^9 passes through the lower die box C , and through the upper die B' , in position to be struck by the reciprocating 15 sleeve E , and forced downward in the position shown in Figs. 2, 3, and 4, carrying the cam plate G^7 , below the pivoted latch G' , thereby allowing the spiral spring G^3 , to carry the latch into engagement with the sliding 20 rod F .

The operation is as follows:—A metal sheet H , is placed upon the upper surface of the upper die B' , when the reciprocating sleeve E , moves downward cutting out a circular 25 blank and carrying it downward upon the shoulder B^3 , and pushing downward the sliding rods F , F' , and G^9 , the downward movement of the rod G^9 being sufficient to carry the cam plate G^7 , below the latch G' , so that the 30 spring G^3 will press the latch against the rod F . The sleeve E , remains at rest holding the edge of the circular blank between the face of the sleeve E , and the shoulder B^3 , of the upper die B' . A continued downward movement of the punch E' , pushes the circular 35 blank through the upper die B' , pushing the rods F , F' , still further downward into the position shown in Fig. 2. The farther continued movement of the central punch E' will 40 press the blank between the face of the punch E' , and the upper surface of the lower die C' , the concentric projection E^2 , entering the opening C^2 , and cutting out the circular disk I , Fig. 3, which is delivered through the tube 45 C^3 , the position of the several parts being shown in Fig. 3. The die E' , is then reversed, allowing the rods F , F' , to move upward and lift the completed blank from the lower die 50 C' , until their movement is limited by the latch G' , as shown in Fig. 4. The rod G^9 , is held in its lowest position by the dwell of the sleeve E , until the punch E' , has reached a 55 position in its upward movement with its lower surface in the same plane as the upper surface of the upper die B' , as shown in Fig. 4, when the sleeve E , is raised allowing the rod G^9 , to be moved upward by the spring G^{11} , thereby carrying the cam plate G^7 , 60 against the latch G' , withdrawing it from the annular notch G , and releasing the sliding rods F , F' , when they will assume their normal position, as shown in Fig. 1, their upward movement being limited by the contact of the rubber washers F^6 , with the annular 65 flange C^4 . The continued upward movement of the cutting sleeve E , and punch E' carries them above the upper die in the position

shown in Fig. 1, to receive another metal sheet when the operation is again repeated.

In the accompanying drawings the sliding 70 rods F , F' , are shown as of equal length and in the construction therein shown only two sliding rods are employed, but it will be obvious that one or more can be used if desired and the rods can be made of varying lengths 75 with the longer rods made to yield.

I do not confine myself so far as the use of the sliding rods F , F' , are concerned to the special form of latching mechanism as shown and described. Neither do I confine myself to 80 the specific construction and arrangement of the sliding rods F , F' , the essential feature of my invention consisting in the employment with a pair of dies having coincident axes and a reciprocating punch passing through 85 one of said dies upon the other, of a gripping device by which the blank is held against the face of the reciprocating punch and thereby carried from one die to the other.

What I claim as my invention, and desire 90 to secure by Letters Patent, is—

1. In a die press, the combination of die boxes B and C placed one above the other with an intervening space D , die B' provided with a shoulder B^3 , die C' with an opening C^2 , 95 the axis of said opening being concentric with the axis of said die B , reciprocating sleeve E , reciprocating die E' sliding concentrically in said sleeve and having a projection E^2 in alignment with said opening C^2 and reciprocating gripping rods F and F' , by which the blank is held against the face of 100 said reciprocating die in its passage between said die boxes, substantially as described.

2. The combination with a pair of dies, and 105 a reciprocating punch acting conjointly with said dies, of gripping rods, by which the blank is held against the face of said reciprocating die, substantially as described, and a latching mechanism, consisting of a sliding latch plate 110 adapted to engage said gripping rods, by which said gripping rods are held from upward movement for the purpose of supporting the completed blank out of contact with the lower 115 of said dies, substantially as described.

3. The combination with a pair of dies having coincident axes and a reciprocating punch 120 acting conjointly with said dies, of sliding rods, by which the blank is held against the face of said reciprocating punch, springs with 125 their tension applied to raise said gripping rods, and a latching mechanism comprising a pivoted latch G' , spring G^3 , sliding rod G^9 , a latch actuating cam plate G^7 , substantially as described.

4. The combination with the sliding gripping rods F , F' , provided with a screw-threaded section, of screw-threaded sleeves F^2 , provided with flanges F^6 , springs F^7 , connecting yoke F^4 , and nuts F^8 , substantially as described.

5. The combination with a pair of dies having coincident axes, and a punch acting 130 conjointly with said dies, of a concentric sleeve E , having a reciprocating motion and acting

conjointly with the upper of said dies, sliding rod G⁹, arranged to be depressed by said sliding sleeve E, cam plate G⁷, carried by the rod G⁹, latch G', and spring G¹¹, by which the motion of the rod G⁹, is reversed, substantially as described.

6. The combination with an annular die B', and a lower die C', having its axis coincident with that of die B', and provided with a concentric opening C², of the tube C⁸, provided with annular flanges C⁴, C⁵, sliding gripping rods carried in said flanges, and springs with

their tension applied to said rods, whereby the blank is held in contact with the reciprocating punch during its downward motion, 15 substantially as described.

Dated at Worcester, in the county of Worcester and State of Massachusetts, this 2d day of July, 1891.

WILLIAM A. TURNER.
